US00D862277S

(12) **United States Design Patent** (10) Patent No.: **US D862,277 S**
(45) Date of Patent: ** Oct. 8, 2019

(54) **SET OF BANDS FOR A FITNESS TRACKER**(71) Applicant: **Fitbit, Inc.**, San Francisco, CA (US)(72) Inventors: **Kenneth S. M. Ling**, San Francisco, CA (US); **Alexander Joseph Ringrose**, Oakland, CA (US); **Patrick James Markan**, San Francisco, CA (US)(73) Assignee: **FITBIT, INC.**, San Francisco, CA (US)(***) Term: **15 Years**(21) Appl. No.: **29/683,107**(22) Filed: **Mar. 11, 2019****Related U.S. Application Data**

(63) Continuation of application No. 29/596,216, filed on Mar. 6, 2017, now Pat. No. Des. 848,875, which is a continuation-in-part of application No. 29/553,318, filed on Jan. 29, 2016, now Pat. No. Des. 800,596, which is a continuation-in-part of application No. 29/521,264, filed on Mar. 20, 2015, now Pat. No. Des. 759,516, which is a continuation of application No. 29/520,607, filed on Mar. 16, 2015, now abandoned.

CLAIM

The ornamental design for set of bands for a fitness tracker, as shown and described.

DESCRIPTION

FIG. 1 is a side elevation view of our new design for a set of bands for a fitness tracker.

FIG. 2 is an isometric view of FIG. 1.

FIG. 3 is an isometric view of FIG. 1 shown with the band exploded off a body for a fitness tracker.

FIG. 4 is an isometric view of the right side band of FIG. 1.

FIG. 5 is another isometric view thereof;

FIG. 6 is a front side elevation view thereof;

FIG. 7 is a back side elevation view thereof;

FIG. 8 is a side elevation view thereof, the other side being a mirror image thereof;

FIG. 9 is a top plan view thereof;

FIG. 10 is a bottom plan view thereof;

FIG. 11 is a front side elevation view of the left side band of FIG. 1;

FIG. 12 is a back side elevation view thereof;

FIG. 13 is a side, elevation view thereof, the other side being a mirror image thereof;

FIG. 14 is a top plan view thereof;

FIG. 15 is a bottom plan view thereof;

FIG. 16 is an isometric view thereof;

FIG. 17 is another isometric view thereof,

FIG. 18 is a close up of the attachment end of the bands of FIG. 3.

FIG. 19 is a side elevation view of our new design for a set of bands for a fitness tracker, all other surfaces being the same as the embodiment of FIG. 1 other than the disclaimed surfaces.

FIG. 20 is an isometric view of FIG. 19.

FIG. 21 is an isometric view of FIG. 19, showing the bands exploded off a body for a fitness tracker.

FIG. 22 is an isometric view of the right side band of FIG. 19.

FIG. 23 is another isometric thereof;

FIG. 24 is a front side elevation view thereof;

FIG. 25 is a back side elevation view thereof;

FIG. 26 is a side elevation view thereof, the other side being a mirror image thereof;

FIG. 27 is a top plan view thereof;

FIG. 28 is a bottom plan view thereof;

FIG. 29 is a front side elevation view of the left side band of FIG. 19;

FIG. 30 is a back side elevation view thereof;

FIG. 31 is a side elevation view thereof, the other side being a mirror image thereof;

FIG. 32 is a top plan view thereof;

FIG. 33 is a bottom side plan view thereof;

FIG. 34 is an isometric view thereof;

FIG. 35 is another isometric view thereof; and,

FIG. 36 is a close up of the attachment end of the bands of FIG. 21.

Stippled shading represents contour, not surface decoration. The broken lines shown in the drawings illustrate environmental subject matter that form no part of the claimed design. The dash-dot-dash lines represent boundary lines that form no part of the claimed design.
